CLAIM

The ornamental design for a water purifier as shown and described.

DESCRIPTION

FIG. 1 is a front perspective view of a water purifier, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an exploded front elevational view of the water purifier;

FIG. 10 is an exploded front perspective view of the water purifier; and,

FIG. 11 is an exploded rear perspective view of the water purifier.

The broken lines in the figures are for the purposes of illustrating portions of the water purifier, which form no part of the claimed design.

1 Claim, 6 Drawing Sheets
